UNITED STATES PATENT OFFICE.

HANS P. G. NORSTRAND, OF CHICAGO, ILLINOIS.

LOCK-SEAM PIPE.

No. 812,288.

Specification of Letters Patent.

Patented Feb. 13, 1906.

Application filed January 24, 1903. Serial No. 140,432.

To all whom it may concern:

Be it known that I, HANS P. G. NORSTRAND, residing at Chicago, Cook county, Illinois, have invented certain new and useful Improvements in Lock-Seam Pipes, of which the following is a specification.

My invention relates to pipes having a longitudinal seam; and the object thereof is to make provision for the holding and locking of the adjacent edges of the pipe and the sealing thereof so as to be fluid-tight.

The novel and advantageous features of construction and operation will be understood from the description hereinafter given.

In the drawings, Figure 1 is a section of a completed pipe embodying my invention, and Figs. 2, 3, and 4 detail views illustrating different steps in the formation of the parts.

A proper understanding of my invention can best be arrived at by following the different steps of the process of formation of the pipe and my novel joint or seam therein, beginning with the plate or sheet and ending with the completed article or pipe. In this connection it may be said that the plate or sheet may be of suitable or desired material and thickness and the resulting pipe of the desired diameter.

Referring first to Figs. 2, 3, and 4, the plate or sheet 1, which is to form the body of the pipe, is rolled over as to two opposite edges, so as to provide thickened portions 2, which are formed by bending the edges of the plate over upon wires 3, as seen in Fig. 2, preferably with the longitudinal axis of the plate passing through the center of the wires to obtain advantages hereinafter explained. After the edges of the plate are turned or bent over, as described, the next step is to roll the plate to a circle, as illustrated in Fig. 3, wherein the edges are shown in proximity, after which the locking-strip 4 is inserted in place, as shown in Fig. 4. In the present instance this locking-strip, which may be of steel, wrought-iron, or other suitable material, is of I-beam section, with the web portion arranged between the edges of the pipe and the top and bottom flanges 6 and 7 thereof respectively located exteriorly and interiorly of the pipe. At the proper time, preferably before the locking-strip is inserted in place, suitable packing 5, either fibrous or metallic, is arranged or laid along the web of the locking-strip so as to be located in the finished pipe between such web and the edges of the pipe, as well as against the top and bot-

tom flanges of the strip. The next step is the pressing together of the parts of the joint by suitable pressing appliances or machinery, such as a hydraulic press, whereby such parts assume the relative position and condition illustrated in Fig. 1. The resiliency or elasticity of the metal of which the pipe is formed gives the loop bent around the wire 2 a tendency to spring out after it is formed, and this tendency, by permitting the loop to yield when the locking-strip is bent over the edges and causing it to spring out again when the pressure is removed, thus maintaining close contact with the inside surfaces of the locking-strip, makes it possible to secure a tight joint. In the completed pipe the locking-strip is bent over upon the enlarged edges of the pipe and substantially incloses them, as shown in Fig. 1, whereby a rigid seam or joint is obtained. Moreover, the packing into which the parts are compressed effectually seals the joint.

As hereinbefore stated, the longitudinal axis of the plate by preference passes through the center of the wires, so that the neutral axis of the shell in a completed pipe passes through the center of the wires. The advantage of this arrangement is that strain on the shell due to internal pressure will be carried uniformly by the inside and outside flanges of the locking-strip, inasmuch as the strain or pull of each half of the enlarged edges will be taken by its respective flange of the locking-strip.

By this arrangement a shoulder is produced at the base of the loop or turn which forms the enlarged edge or terminal portion, and this, coöperating with the shoulder formed by the bending over of the corresponding flange of the locking-strip, causes any strain tending to open the seam to fall more directly on the sheet metal, and thus prevents the uncoiling of the turned-over portion.

I claim—

1. A lock-seam pipe, comprising the pipe proper formed of sheet metal and having a longitudinal seam, wires extending longitudinally of the pipe and over which the longitudinal edges of the pipe are turned to form enlarged terminal portions having a shoulder at the base of the turn, and a locking-strip arranged to be bent over and clamped around said enlarged terminal portions, said locking-strip having a shoulder adapted to coöperate with the shoulder on the enlarged terminal portion.

2. A lock-seam pipe comprising the shell or pipe proper formed of sheet metal and having a longitudinal seam, wires over which the longitudinal edges of the pipe are turned, and whose longitudinal axis lies on the neutral axis of the shell, and a locking-strip engaging and holding such edges to lock the joint or seam.
3. A lock-seam pipe having a longitudinal seam and comprising the shell or pipe-body formed of sheet metal, wires over which the longitudinal edges are flat and of a thickness uniform with the shell, wires over which such edges are turned and whose longitudinal axis lies on the neutral axis of the shell, and a locking-strip engaging and holding such edges to lock the joint or seam.
4. A lock-seam pipe having a longitudinal seam and comprising the shell or pipe-body formed of sheet metal, wires over which the longitudinal edges of the pipe are turned to form a shoulder at the base of the turn, and a locking device consisting of an I-shaped strip whose flange portions are bent over the edges of the pipe with their extreme ends abutting the body of the pipe, one of said flange portions forming a shoulder adapted to coöperate with the shoulder at the base of the turn, whereby such flange portions embrace such edges and lock the joint or seam.
5. A lock-seam pipe having a longitudinal seam, and comprising the shell or pipe-body formed of sheet metal, wires over which the longitudinal edges of the pipe are turned to form enlarged terminal portions having a shoulder extending along the base of the turn, and a locking device consisting of an I-shaped strip whose flange portions are bent over the enlarged terminal portions of the pipe, one of said flange portions forming a shoulder adapted to coöperate with the shoulder at the base of the turn, and packing arranged in the inner corners of the locking-strip to seal the joint or seam.
6. A lock-seam pipe, comprising the pipe proper formed of sheet metal and having a longitudinal seam, the edges of said pipe being turned back upon themselves in an open loop to form enlarged and elastic terminal portions, and a locking-strip engaging and holding such enlarged and elastic terminals to lock the joint or seam.
7. A lock-seam pipe, comprising the pipe proper formed of sheet metal and having a longitudinal seam, wires over which the longitudinal edges of the pipe are turned, without being brought into close contact therewith, to form enlarged and elastic terminal portions, and a locking-strip arranged to engage and hold said portions to lock the joint or seam.
8. A lock-seam pipe, comprising the pipe proper formed of sheet metal and having a longitudinal seam, the longitudinal edges of the pipe adjacent to the seam being turned back upon themselves in an open loop to form elastic enlargements, and a locking-strip of substantially I-beam section whose web portion is arranged between the edges of the pipe, and whose top and bottom flanges are pressed upon and substantially surround said elastic enlargements.
9. A lock-seam pipe, comprising the pipe proper formed of sheet metal and having a longitudinal seam, wires over which the longitudinal edges of the pipe are turned to form a substantially cylindrical enlargement whose longitudinal axis lies in the neutral axis of the shell of the pipe, and a locking-strip of substantially I-beam section arranged to engage and hold said edges.
10. A lock-seam pipe, comprising the pipe proper formed of sheet metal and having a longitudinal seam, the longitudinal edges of said pipe being turned back on themselves in an open loop to form elastic enlargements of rounded exterior, a locking-strip of substantially I-beam section arranged to engage and hold such enlarged edges, and packing interposed in the space lying between the rounded exterior of said enlargements and the angular interior surfaces of said I-beam locking-strip.
11. A lock-seam pipe, comprising the pipe proper formed of sheet metal and having a longitudinal seam, wires extending along the edges of the pipe adjacent to said seam and over which the edges of the pipe are turned, without being rigidly secured thereto to form a shoulder at the base of the turn, and a locking-strip arranged to engage and hold said edges, said strip having a portion adapted to coöperate with said shoulder.
12. A lock-seam pipe, comprising the shell proper having a longitudinal seam, wires extending along said seam over which the longitudinal edges of the pipe are turned, but not rigidly secured thereto, the longitudinal axes of said wires lying in the neutral axis of said pipe, and a locking-strip clamped upon said edges to lock the joint or seam.
13. A lock-seam pipe, comprising the pipe-body formed of sheet metal and having a longitudinal seam the edges of said pipe-body being turned back upon themselves in an open loop the base of which projects outside of the plane of the pipe to form a shoulder, said loop forming an enlarged terminal portion, and a locking-strip adapted to embrace the said terminal portions and having a shoulder adapted to coöperate with the shoulder at the base of the turn.
